UNITED STATES PATENT OFFICE.

FREDERICK W. LANE, OF CHICO, CALIFORNIA, ASSIGNOR TO THE DIAMOND MATCH COMPANY, OF CHICAGO, ILLINOIS, A CORPORATION OF ILLINOIS.

MEANS FOR TREATING MATCH- SPLINTS WITH POWDERED MATERIAL.

1,230,416.

Specification of Letters Patent. Patented June 19, 1917.

Application filed October 19, 1916. Serial No. 126,503.

To all whom it may concern:

Be it known that I, FREDERICK W. LANE, a citizen of the United States, and resident of Chico, in the county of Butte and State of California, have invented certain new and useful Improvements in Means for Treating Match-Splints with Powdered Material, of which the following is a specification.

This invention relates to means for treating match splints with powdered material, such as ammonium phosphate, adapted to render the splints non-glowing when they have been ignited and the flame extinguished.

15 The object of my invention is to provide for the economical, efficient and uniform application of powdered material to and throughout the exposed surfaces of the splints during the operation of converting them into matches on a continuous match making machine of the kind in which an endless carrier is employed.

The invention, broadly considered, comprises a chamber arranged in the route of 25 the splint carrier of the match machine, said chamber having an inlet and outlet for the carrier, means for effecting a fall of anti-glowing powder within the chamber, throughout its width, or substantially so, 30 during the travel of the carrier, and means for deflecting the carrier through a path below and laterally of the falling powder, whereby the projecting splints throughout the width of the carrier are caused to progress to and through the descending powder 35 in said chamber.

More specifically, the invention comprises a chamber of the character mentioned, having means for guiding the carrier in a loop-like course, with the splints pointing toward 40 each other, within the zone of the falling powder.

The invention also comprises a chamber of the character mentioned, having means arranged in co-operative relation to the traveling splints, adapted more effectually to apply the powder to the exposed surfaces of the splint material.

45 The invention also comprises novel features of construction and combinations of parts, all of which will be hereinafter particularly described and claimed.

In the drawings—

Figure 1 is a side elevation, partly in 55 section, of an apparatus embodying the prin-

ciple of my invention, a fragment of the endless carrier, as supplied with match splints, being indicated.

Fig. 2 is a transverse horizontal section, as on the line 2—2 of Fig. 1.

Fig. 3 is a vertical section through the lower part of the casing, as on the line 3—3 of Fig. 2.

Fig. 4 is a sectional end elevation of the apparatus, as on the line 4—4 of Fig. 1.

Fig. 5 is a perspective view of a part of the carrier, with splints therein, in the region of the spaced powder-applying elements, some of which latter are shown.

Fig. 6 is a detail of several of said elements.

Referring to the drawings, 10 designates a part of a splint carrier of any usual or approved type. The construction illustrated comprises a series of perforated plates 75 hinged or linked together at their edges to form an endless chain, into the perforations of which plates rows of match splints (S) are inserted and thus transported in spaced relation to each other throughout the match-making path. Suitably-located in the route of the carrier, after it leaves the splint inserting station, is a structure providing a relatively capacious chamber into and through which the carrier with its load of 80 splints is guided, said splints during their travel within the chamber being treated with an anti-glowing material, such, for example, as finely-divided ammonium phosphate.

This structure in its preferred form comprises a Ω-shaped body plate 11, spaced side walls 12 and a double-inclined or V-shaped floor 13; the body plate, which constitutes the ends and top of the structure, being provided adjacent to the respective ends of the 95 floor with an inlet 14 and outlet 15 for the splint carrier. Within the chamber of the casing thus provided are suitably-arranged guide elements which are adapted to deflect the carrier from a horizontal path during 100 its travel through the chamber. In the present instance there are three guide wheels 16, 17 and 18, whereof one (16) is arranged in the upper part of the chamber and the others are arranged in spaced relation to each other adjacent to the inlet and outlet respectively; whereby the carrier as it passes into, through and from the chamber is supported and guided in an upward and downward or loop-like course with the oppositely- 110

projecting rows of splints traveling in proximity to each other as the carrier moves about the lower wheels 17, 18, as clearly illustrated in Figs. 1 and 3. The guide wheels are or may be the usual skeleton type employed in match machines; said wheels being borne by parallel shafts 19 mounted in suitable bearings on the supporting frame work. During the upward and downward travel of the lower portions of the loop of the carrier within the chamber, the projecting splints throughout the width of the carrier pass through a shower of anti-glowing powdered material and are thereby effectually coated. A typical means for producing an adequate down-pour of powder is herein illustrated and will now be described.

Arranged exteriorly of the casing is an elevator-leg comprising a housing 20 and a bucket conveyer 21 traveling about wheels 22, 23 at the upper and lower ends of the housing respectively; the shaft 24 of the upper wheel being provided with a pulley 25 which is driven from a suitable source of power. At the lower end of the housing is a hopper 26 having a hinged cover 27 which may be opened to permit the introduction of powdered material to the hopper as desired, such material being thence scooped up and raised by the succession of traveling buckets; and at the upper end of the housing is a bin 28 into which the powder is discharged when the buckets pass over the wheel 22. The hopper and bin are provided with laterally-extending trough or channel members 29, 30 respectively, which are slid into the chamber through entrance tubes 31, 32 in that side of the casing adjacent the elevator-leg. These members extend transversely of the chamber throughout its entire width or substantially so; the trough 30 being disposed centrally of the space between the two lower guide wheels, on a plane somewhat above their axes, and the trough 29 being located in the channel in the floor of the chamber.

Within the upper and lower troughs are oppositely-pitched screw-conveyers 33, 34 respectively, the shafts of which have their bearings in the inner ends of the troughs and in the outer side of the elevator housing; whereby the elevator-leg and its appurtenances can be bodily removed from or applied to the casing, as desired. The conveyer shafts are equipped with pulleys 35 which are connected by means of a belt 36; the upper shaft being provided with a pulley 37 which is belted with a pulley 38 on the power-driven shaft 24. Thus the two screw conveyers are concurrently driven. The upper conveyer in its rotation progressively feeds the powder from the bin 28 of the elevator-leg into and along the trough 30, which powder overflows the sides 65 of the trough and pours upon and into inti-

mate contact with the underlying splints, throughout the width of the carrier, as they travel upward and downward about the respective wheels 17, 18; and the lower conveyer in its rotation removes from the chamber and discharges into the hopper 26 of the elevator-leg the accumulation of powder upon the bottom of the chamber.

In order more effectually to distribute the powder among the adjacent splints and to rub the powder well into the surfaces of the splints, and thus insure their efficient "impregnation", I provide within the chamber a plurality of traveling frictional elements which are located within the zone of the falling powder and are adapted to contact with or travel in close relation to the sides of the individual splints throughout the exposed surface of the latter. A preferred form of the said elements and their actuating mechanism is herein shown and will now be described.

Mounted within the chamber, directly above the screw-conveyer 33, is a freely rotatable roller 39 having a plurality of circumferential grooves 40 corresponding in number and relative position with the vertical spaces between the rows of match splints on the carrier. A shaft 41, carrying a similarly grooved roller 42, is mounted within the chamber directly above the lower screw conveyer, and the two rollers support in their corresponding grooves a series of endless strands 43 of flexible material which are concertedly driven. In the present instance the shaft 41 is provided with a pulley 44 which is driven from a suitable source of power so as to actuate the roller 42 and impel the strands at a relatively high speed. These strands are so arranged as to travel in the spaces between the respective rows of splints as the splints are progressing about the lower guide wheels 17, 18, the vertical runs or stretches of the strands moving in the same general vertical direction as the proximate splints. The strands are preferably composed of spring belting in order that each strand shall be maintained taut by its inherent elasticity; but in lieu of the spring construction any other suitable material may be employed. As the splints round the wheel 17 they approach the upwardly traveling stretches of the strands and gradually pass into the spaces between adjacent strands until the splints reach a horizontal position, or substantially so, whereupon the splints as the carrier is deflected on the wheel 17 toward the wheel 16 are caused to recede from the strands. Similarly, when the splints round the wheel 18 they enter between and recede from the adjacent stretches of the strands. Thus the splints in their travel about the wheels 17, 18 are individually subjected to the lateral rubbing action of the strands throughout

substantially the length of the splints, and at the same time the powder is well scattered and distributed among the splints by the rapidly traveling strands.

5 I preferably arrange immediately above the lower roller 42, a removable pan 45 having a perforated bottom 46, which pan receives any splints or slivers which may be detached from the carrier by the frictional action of the strands. One side of the casting is provided with a suitable opening whereby the pan can be readily inserted into or removed from the chamber as desired, such opening having a suitable door, as 47.

10 15 I also preferably support within the casting, adjacent the vertical runs of the strands and just above the pan 45, two horizontal comb bars 48, the teeth of which correspond with and extend into the spaces between the 20 adjacent strands, thus serving to maintain the strands in parallel relation to each other during their travel in the region of the splints.

It is to be understood that the particular 25 construction herein illustrated and described is designed to exemplify the principle of my invention, and that therefore the mechanism may be considerably modified and still be within the scope of the appended 30 claims.

I claim—

1. In a match machine having a splint carrier, a chamber having an inlet and outlet for the carrier, means for guiding the carrier with its splints upwardly within the 35 chamber, and means for effecting a fall of anti-glowing powder upon the upwardly traveling splints within the chamber.

2. In a match machine having a splint carrier, a chamber having an inlet and outlet for the carrier, means for guiding the carrier, with its splints, upwardly and downwardly within the chamber, and means for supplying powder to and among the splints 45 during their upward and downward travel within the chamber.

3. In a match machine having a splint carrier, a chamber having an inlet and outlet for the carrier, means for guiding the carrier, with its splints, in a loop-like path within the chamber, and means embraced by the loop of the carrier for effecting a fall of anti-glowing material upon and among the splints on the oppositely-moving lower portions of said loop.

4. In a match machine having a splint carrier, a chamber having an inlet and outlet for the carrier, means for guiding the carrier, with its splints, in a loop-like path 50 within the chamber, an elevator-leg, means for feeding anti-glowing powder from the bottom of said chamber to the lower portion of the elevator-leg, and means for feeding the powder from the top of the elevator-leg 55 to the interior of the chamber and discharg-

ing it upon and among the splints on the lower portions of the loop of the carrier.

5. In a match machine having a splint carrier, a chamber having an inlet and outlet for the carrier, means for guiding the carrier, with its splints in a loop-like path within the chamber, an elevator-leg having upper and lower troughs extending transversely of the chamber, the upper trough being embraced by the loop of the carrier, 70 means for feeding anti-glowing powder from the lower trough to the bottom of the elevator-leg, and means for feeding the powder from the top of the elevator-leg to and along the upper trough. 75

6. In a match machine having a splint carrier constructed to support rows of splints in spaced relation to each other, a chamber having an inlet and outlet for the carrier, means for deflecting the carrier in its passage through said chamber, a series of spaced elements adjacent the deflected portion of the carrier, whereby the splints in such portion are caused to enter and recede from the spaces between adjacent elements, 85 and means for effecting a fall of anti-glowing material upon and among the splints on the deflected portion of the carrier. 90

7. In a match machine having a splint carrier constructed to support rows of splints in spaced relation to each other, a chamber having an inlet and outlet for the carrier, means for deflecting the carrier in its passage through said chamber, a series of spaced endless strands, means for continuously moving them adjacent the deflected portion of the carrier, whereby the splints in such portion are caused to enter and recede from the spaces between adjacent strands, and means for effecting a fall of 105 anti-glowing material upon and among the splints on the deflected portion of the carrier. 100

8. In a match machine having a splint carrier constructed to support rows of splints in spaced relation to each other, a chamber having an inlet and outlet for the carrier, means for deflecting the carrier in its passage through said chamber, a series of spaced endless strands of spring material, 110 rollers upon which the strands are supported and thereby continuously driven adjacent the deflected portion of the carrier, whereby the splints in such portion are caused to enter and recede from the spaces between adjacent strands, and means for effecting a fall of anti-glowing material upon and among the splints on the deflected portion of the carrier. 115

9. In a match machine having a splint carrier constructed to support rows of splints in spaced relation to each other, a chamber having an inlet and outlet for the carrier, means for guiding the carrier with its splints in a loop-like path within the 120 chamber, an elevator-leg, means for feeding anti-glowing powder from the bottom of said chamber to the lower portion of the elevator-leg, and means for feeding the powder from the top of the elevator-leg 125 to the interior of the chamber and discharg-

chamber, a series of spaced endless strands, rollers upon which the strands are supported and thereby continuously driven adjacent the lower portions of the loop of the carrier, whereby the splints in such portions are caused to enter and recede from the spaces between adjacent strands, and means for effecting a fall of anti-glowing material upon and among the splints on the said lower loop portions of the carrier.

10. In a match machine having a splint carrier constructed to support rows of splints in spaced relation to each other, a chamber having an inlet and outlet for the carrier, means for guiding the carrier with its splints in a loop-like path within the chamber, a series of spaced endless strands, rollers upon which the strands are supported

and thereby continuously driven adjacent the lower portions of the loop of the carrier, 20 whereby the splints in such portions are caused to enter and recede from the spaces between adjacent strands, an elevator-leg, means for feeding anti-glowing powder from the bottom of said chamber to the 25 lower portion of the elevator-leg, and means for feeding the powder from the top of the elevator-leg to the interior of the chamber and discharging it upon and among the splints on the lower portions of the loop of 30 the carrier.

Signed at Chico in the county of Butte and State of California October 10, A. D. 1916.

FREDERICK W. LANE.
